DESIGN FOR A NOZZLE FOR A MASSAGING INSTRUMENT OR SIMILAR ARTICLE

Percy O. Johnson, Columbus, Ohio

Application May 28, 1934, Serial No. 51,940

Term of patent 3½ years

To all whom it may concern:

Be it known that I, Percy O. Johnson, a citizen of the United States, residing at Columbus, in the county of Franklin and State of Ohio, have invented a new, original, and ornamental Design for a Nozzle for a Massaging Instrument or Similar Article, of which the following is a specification, reference being had to the accompanying drawing, forming a part thereof.

Fig. 1 is a perspective view of the nozzle for a massaging instrument or similar article showing my new design;

Fig. 2 is a vertical longitudinal sectional view thereof.

I claim:

The ornamental design for a nozzle for a massaging instrument or similar article, as shown.

PERCY O. JOHNSON.
